UNITED STATES PATENT OFFICE.

GEORGE L. FREETO, OF MECHANICSBURG, ILLINOIS.

ACETYLENE-GENERATOR.

1,141,182.

Specification of Letters Patent.

Patented June 1, 1915.

Application filed December 7, 1912. Serial No. 735,545.

To all whom it may concern:

Be it known that I, GEORGE L. FREETO, a citizen of the United States, residing at Mechanicsburg, in the county of Sangamon and State of Illinois, have invented new and useful Improvements in Acetylene-Generators, of which the following is a specification.

My invention relates to acetylene generators, especially to the type known as pit generators or generators which are sunk or set into the ground.

An object of the invention is to provide an auxiliary means to supply a quantity of calcium carbid to a generator upon the exhaustion of the main supply.

A further object of the invention is to generally improve the construction of a device of this kind.

The preferred embodiment of my invention is hereinafter described and illustrated in the accompanying drawings.

In these drawings:—Figure 1 is a vertical sectional view of my generator. Fig. 2 is a plan view of the supply hopper and the auxiliary hopper, and, Fig. 3 is a detail sectional view illustrating the auxiliary hopper in connection with the main hopper, which is partly broken away.

Referring to the drawings, the generator is located or sunk in a pit and comprises a main tank 1, between which and the earth, is provided a suitable cement casing 2. Said tank is provided with a cover 3 removably secured in any suitable manner, as by means of engagement with a hook or hooks 4 and a staple 5, which may be engaged by a padlock or the like to lock the cover. Within the tank 1 is secured a smaller water containing tank 5' on which rests a calcium carbid supply hopper 8, whose bottom is funnel-shaped, terminating in a tube 9, to which is pivoted a nozzle such as 10 which has a weight 11 attached thereto. A suitable

rod 12 which extends above the hopper, is pivoted to the nozzle 10 at a point designated as 42. Below the nozzle 10, and secured to the bottom of supply hopper 8 is a shoe such as 13. A suitable cross arm 14 is secured in the hopper 8, and has extending therefrom rearward arms 15 to which is pivoted at 16, an auxiliary hopper 17.

Adjacent the hopper 17 is pivoted a tray 18 at 19, which tray normally bears against the hopper 17, and one wall 20 of which hopper 17 prevents the discharge of the con-

tents of the tray. A wire or rod such as 21 is secured to the hopper 17, one end of rod 21 being attached to wall 20 of hopper 17, the center of said rod being secured to the opposite wall of hopper 17 and the other end terminating at a point adjacent the top of hopper 8. A hook 22 provided on a suitable bent wire 23, projects through an elongated slot provided in the hopper 8 and engages the tray 18, as shown. Said wire 23 at the opposite end terminates in a handle portion 24 located adjacent the top of the generator.

A suitable purifier device is provided inside of tank 51 and consists of a receptacle 25 adapted to contain hair, wool or other suitable purifying agent, and is provided with a perforated cover 26. The receptacle 25 is secured to a suitable pipe 27 located within the tank 5', which pipe is connected to a pipe 28 by means of a cross pipe 29. A pipe 30 leading to a building, storage tank or the like, is connected to the pipe 28. At the top of pipe 28, adjacent the top of the generator, is provided any suitable form of cut off valve 32.

The numeral 37 designates a suitable removable bell adapted to inclose the hopper 8, and extend part way over tank 5'. Said bell at its top is provided with an outlet 39 having a cut off valve 38 therein. A handle 40 for the bell, is suitably pivoted vertically to the top of the bell, and at one end is connected to the valve 38 so that in addition to being a handle, the member 40 is an actuating member for the valve 38.

In operation, water is supplied to the outer tank 1 and water tank 5'. Calcium carbid is supplied to the hopper 8, auxiliary hopper 17, and auxiliary hopper 18. Valves 38 and 32 are closed, and the cover 3 locked in place. The calcium carbid is supplied through the tube 9 and nozzle 10 onto the shoe 13, falling into the water contained within the tank 5', whereupon a chemical reaction takes place between the calcium carbid and water, producing acetylene gas. Said gas rises and its only escape from the generator is through the perforated cover 26 of the purifier. After passing through said cover 26, the gas also passes through the purifying medium in the receptacle 25 and out through pipes 27, 29, 28 and 30 to a building or suitable storage. When the supply of gas becomes low in the generator, the bell 37 descends. In so doing the same strikes against the rod 12 and actuates

the nozzle 10 about the pivoting point 41, and moves the weighted side thereof upwardly so as to increase the extent of the supply opening between tubes 9 and shoe 13, whereby the calcium carbid may be fed more rapidly. When the gas volume increases, the bell moves upwardly and disengages the rod 12, whereupon the weight 11 will restore the same to normal position, which 10 is the position shown in Fig. 1. When the supply of calcium carbid has become exhausted the bell is in its lowermost position and rests upon the top of the hopper 8, depressing the rod 12. When the exhaustion 15 of the calcium carbid in hopper 8 occurs, the cover 3 is removed and the rod 24 is pulled upwardly which causes the hook 22 to disengage from supporting relation to the tray 18, allowing the tray to tilt and cause 20 a contained supply of calcium carbid to be emptied into hopper 8 and the water in tank 5'. Auxiliary hopper 17, which normally depends upon the hook 22 and tray 18 for its support in an upright position, 25 is now freed from this device, but tilting of hopper 17 is effectively prevented by the position of bell 37 directly over rod 21. The gas generated from the calcium carbid supplied from the tray is sufficient to raise the 30 bell 37, which bell in rising, releases the rod 21. The auxiliary hopper 17 which contains an auxiliary supply of calcium carbid, having been deprived of its support by the release of tray 18 from hook 22, is now 35 free to tilt or empty its contents into the water contained in tank 5'. This auxiliary supply of calcium carbid may be of any quantity desired, but is preferably of sufficient quantity to supply gas for several 40 hours.

In supplying calcium carbid to the hopper 8, the cover 3 is removed, and valve 32 opened to permit the escape of any gas contained within the supply pipes. Upon the 45 escape of the gas from the pipes the handle 40 is actuated so as to open the outlet 38, through which outlet any gas contained within the bell may escape. Thereupon the bell 37 may be removed without danger of 50 encountering contained gas.

It is clear that changes within the details of construction may be made without departing from the spirit and scope of my invention.

55 Having thus described my invention, what I claim is:—

1. The combination in an acetylene generator, of a main carbid supply hopper, an emergency hopper positioned in said main 60 hopper and adapted to contain an auxiliary

supply of calcium carbid, said emergency hopper pivoted out of equilibrium, an emergency tray also adapted to support a charge of carbid hinged to said emergency hopper and positioned to normally support the emergency hopper in equilibrium, a bent wire positioned to normally support the emergency tray and thereby the hopper, and means for releasing the bent wire from such supporting relation with the emergency tray 65 and hopper, substantially as described. 70

2. The combination in an acetylene generator, of a main carbid supply hopper, an emergency hopper positioned in said main hopper and adapted to contain an auxiliary 75 supply of calcium carbid, a bell over said emergency hopper adapted to engage therewith upon the exhaustion of the gas in said generator, said emergency hopper pivoted out of equilibrium, an emergency tray also 80 adapted to support a charge of carbid hinged to said emergency hopper and positioned to normally support the emergency hopper in equilibrium, a bent wire positioned to normally support the emergency 85 tray and thereby the hopper, means for releasing the bent wire from supporting relation with the tray to allow the tray to dump its charge of calcium carbid into the generator, whereby the bell may ascend from 90 engagement with the emergency hopper, substantially as described.

3. The combination in an acetylene generator, of a carbid supply hopper, a bell, an emergency hopper carried by said carbid 95 supply hopper, an emergency tray carried by the emergency hopper, said emergency hopper pivoted in the carbid hopper out of equilibrium and normally held in equilibrium by a hook in engagement with the 100 emergency tray, a hook adapted to normally support said emergency tray and thereby said emergency hopper, a balancing rod secured to said emergency hopper and adapted to support the emergency hopper in equilibrium after the withdrawal of the hook from supporting relation with the emergency tray 105 by engagement with the bell when the bell is at its lowest position, whereby a charge of carbid is dumped into the carbid supply 110 hopper upon the raising of the bell occasioned by the generation of gas from carbid dumped from the emergency tray, and means for releasing the hook from supporting relation with the emergency tray, substantially as described. 115
